TWO SIDE, TOP AND BOTTOM CHIPPERS IN SERIES

Lionel Pease, Seattle, Wash., assignor, by mesne assignments, to Thomas W. Secrest as trustee of the Creditors' Committee of Mill Equipment, Inc.

Filed Dec. 18, 1964, Ser. No. 419,333
6 Claims. (Cl. 144—3)

This invention relates to a method and apparatus for the conversion of logs and the like to wood construction members and wood chips.

Generally speaking, small trees are not economical to use. For example, a small tree does not have many board feet of lumber. To cut the tree, convey it to a central processing location, remove the bark, saw off the side slabs, and make a small cant from the logs is not economically feasible. In many instances it costs more to process a small tree as above illustrated than can be realized from the sale of the resulting cant or cants. Because of this many small trees are not cut or not taken from the forest to be processed into a small cant having a square cross-sectional configuration or a rectangular cross-sectional configuration. The loss of such potentially usable wood is large. Further, as the larger and older merchantable forests are being cut there are more small trees and fewer large trees.

In regard to large trees in certain instances the wood in these large trees is not fully utilized with present day equipment and processes and therefore may be considered to be wasted.

From having worked with wood and woodworking equipment for many years I have invented a machine which makes it economically feasible to reduce a log to wood chips and a wood member having a cross-sectional configuration of an octagon or having a cross-section of an octagonal configuration.

This wood construction member of an octagonal cross-sectional configuration may be employed for log building such as houses and halls, decorative beams in buildings, fences, posts, rails, posts for pole barns and warehouse construction, piling, and the like.

Accordingly, one of the advantages of this invention is the provision of a method and apparatus for the utilization of a waste material to make useful products, such as wood chips and wood construction members; to quickly convert wood into wood construction members and wood chips; to make decorative wood construction members; and to make wood construction members of a substantially uniform cross-sectional area and configuration.

These other important objects and advantages of the invention will be more particularly brought forth with reference to the accompanying detailed specification, the appended claims, and the drawings.

In the drawings:

FIGURE 1 is a schematic plan view of the invention comprising a machine for converting a log to a wood construction member having an octagonal cross-sectional configuration;

FIG. 2, taken on line 2—2 of FIG. 1, is a lateral cross-sectional view looking at the first two chippers and which two chippers move toward and away from each other in a vertical path;

FIG. 3, taken on line 3—3 of FIG. 1, is a lateral cross-sectional view looking at the second set of two chippers and which two chippers move toward and away from each other in a horizontal path;

FIG. 4, taken on line 4—4 of FIG. 1, is a lateral cross-sectional view looking at the third set of two chippers and which two chippers move toward and away from each other at an angle of forty-five degrees (45°) with

2

respect to the chippers of FIG. 2 and also the chippers of FIG. 3;

FIG. 5, taken on line 5—5 of FIG. 1, is a lateral cross-sectional view looking at the fourth set of two spaced apart chippers and which chippers move toward and away from each other at an angle of forty-five degrees (45°) with respect to the chippers of FIG. 2 and the chippers of FIG. 3, and move at an angle of ninety degrees (90°) with respect to the chippers of FIG. 4;

FIG. 6 is a lateral cross-sectional view of a log, looking at the small end of the log, and shows by cross-hatching that portion of the log which is removed as wood chips by the chippers of FIG. 2;

FIG. 7 is a lateral cross-sectional view of the partially processed log after leaving the chippers of FIG. 2, and shows by cross hatching that portion of the log which is removed as wood chips by the chippers of FIG. 3;

FIG. 8 is a lateral cross-sectional view of the partially processed log after leaving the chippers of FIG. 3 and shows by cross hatching that portion of the log which is removed as wood chips by the chippers of FIG. 4;

FIG. 9 is a lateral cross-sectional view of the partially processed log after leaving the chippers of FIG. 4 and shows by cross hatching that portion which will be removed as wood chips by the chippers of FIG. 5;

FIG. 10 is a lateral cross-sectional view of the wood construction member and shows this member, in the lateral cross-sectional view, as having an octagonal configuration;

FIG. 11, taken on line 11—11 of FIG. 1, is a lateral cross-sectional view looking at the feed rolls for positioning the partially processed log after it has passed through the chippers of FIG. 2;

FIG. 12, taken on line 12—12 of FIG. 1, is a lateral cross-sectional view of the feed rolls for positioning the partially processed log after leaving the chippers of FIG. 3 and before coming in contact with the chippers of FIG. 4;

FIG. 13, taken on line 13—13 of FIG. 1, is a lateral cross-sectional view of the partially processed log after it has left the chippers of FIG. 4 and before coming in contact with the chippers of FIG. 5;

FIG. 14, taken on line 14—14 of FIG. 1, is a lateral cross-sectional view looking at the feed rolls for handling the wood construction member after it has passed through the chippers of FIG. 5;

FIGS. 15 and 16 are lateral cross-sectional members of the smaller end of a log and the larger end of a log respectively, and show by cross hatching that portion of the log which will be removed as wood chips and by the clear area that portion of the log which will become the wood construction member;

FIG. 17 is a fragmentary plan view looking down on the wood construction member having, in the lateral cross-sectional view an octagonal configuration, and which member is used as a support post and to which are nailed wall members at a 90° angle to each other and a bracing member at an angle of 45° to each wall member; and,

FIG. 18 is a fragmentary side elevational view of the wood construction member used as a post for supporting beams and illustrates bracing members nailed at a 45° angle to the post and to the beam.

The object of this invention is to provide a method and apparatus for producing a wood construction member 20 having a lateral cross-sectional configuration of a generally octagonal configuration as illustrated in FIG. 10. With reference to FIGS. 15 and 16, it is seen that a portion of the log is removed to produce the member 20. FIG. 15 may be considered to be the small end 21 of the log, or near the top of the tree, and FIG. 16 may be considered to be the large end 23 of the log or the lower end

of the tree. The first set of two spaced apart chippers remove as wood chips the cross-hatched portion 22. The second set of two spaced apart chippers remove as wood chips the cross-hatched portion 24. The third set of two spaced apart chippers remove as wood chips across-hatched portion 26. And, the fourth set of two spaced apart chippers remove as wood chips the cross-hatched portion 28. The result is the wood construction member 20 having in a lateral cross-sectional view an octagonal configuration.

At the present time it is possible to produce the wood construction member 20 by sawing away the log or sawing slabs off the log. From the best information available to me, it takes approximately twenty to thirty minutes to make a wood construction member 20 by the process of sawing slabs off a log. The length of the wood construction member is approximately fifty feet. The diameter of the wood construction member is of secondary importance as a saw is not affected to any great degree by the diameter of the tree. One of the reasons for this long time to saw a log into the octagonal configuration is to set up and align the saws and the log to accurately remove the slabs from the log. As contrasted with the time of twenty to thirty minutes to convert the fifty foot log into a wood construction member 20 having an octagonal configuration in the lateral cross-sectional view, my invention makes it possible to convert such a log into the wood construction member 20 in approximately fifteen to twenty seconds. The saving in time is readily apparent. Further, there is a saving in money as the material removed from the log to make the wood construction member 20 is converted into wood chips which may be used to make wood pulp in pulping operations for paper and kraft paper and the like, to make dissolving cellulose, to make chips for chip core, hardboard, softboard, fiberboard, and the like. With the sawing process the slabs may be burned to get rid of them or else may be rehandled and put through a chipping machine. The process of separately handling the slabs or sawed off portions of the log is expensive, time consuming and in many instances makes impractical to use the sawed off portion of the log. In regard to the production of wood chips there is produced in the sawing operation a lot of sawdust which is discarded or wasted while in the chipping process there is no sawdust and therefore less waste. Further, the many steps in the handling of a log to saw it into a wood construction member having an octagonal configuration in the lateral cross-sectional view is expensive. As a result of this expense, the cost of wood construction members similar to 20 is too expensive for extensive use.

In FIG. 1 there is schematically illustrated a plan view of one embodiment of my invention 29. The invention 29 may be considered as embodying a first machine 30 comprising a first set of chippers 32 and a second set of chippers 34 and a second machine 40 comprising a first set of chippers 42 and a second set of chippers 44; and, a feed table 50. There is one machine 29 which may be considered to be composed of two machines 30 and 40, for converting a log to a wood construction member 20 having in a lateral cross-sectional view an octagonal configuration. For ease of visualization a phantom line 41 may be used to divide 29 into 30 and 40. In an installation, each half 30 and 40 of the machine 29 may be easily set at an angle of 22½° with the vertical. As is easily visualized the log is converted into the wood construction member 20 by the four sets of chippers 32, 34, 42, and 44.

It is to be remembered that there is sufficient supporting structure for supporting the chippers and associated motors, feed rolls and associated motors, and other auxiliary equipment. This supporting structure is not illustrated as it may be varied to suit the size of chipper and motor to be used. For small logs there will be employed a relatively small chipper and associated motor. For large logs it will be necessary to have larger chippers and larger motors. Therefore, the supporting structure, both as to length of the machine and individual members, will vary.

The chippers 32 comprise a top chipper 36 and a bottom chipper 38. The chippers 36 and 38 are attached to the output shafts of motors 46. It is to be understood that the chippers have chipper teeth 33. There is a framework 48 having an upper rail 52 and a lower rail 54 and side members or stiles 56.

Attached to the upper rail 52 is a plate 58. Attached to the plate 58 is a fluid actuated cylinder 60 having a plunger 62. In fact, the plunger 62 is common with fluid actuated cylinder 64. A cylinder 66 is in a back-to-back relationship with the fluid actuated cylinder 64. The fluid actuated cylinder has a plunger 68 which connects with an attaching means 70. It is seen that on the rail 54 there is a plate 72. A similar set of cylinders is attached to the plate 72. Therefore, the same reference numerals will be employed for like cylinders. The cylinders 60, 64, and 66 with associated plungers, move the two chippers 36 and 38 vertically and move the two chippers towards each other or away from each other. The two chippers 36 and 38 remove wood chips from a wood member so as to have two substantially parallel surfaces.

The apparatus 30 also comprises a second set of chippers 34. In FIG. 3 it is seen that there is a left chipper 74 and a right chipper 76. These chippers 74 and 76, with associated motors 46, are carried in a frame 78. The frame 78 is essentially the same as the frame 48 and therefore where possible like reference numerals will be employed. The frame 78 comprises an upper rail 80 and a lower rail 82. These two rails are connected by stiles 84 and 86. On the stile 84 there is a plate 88. A series of fluid actuated cylinders connect with the plate 88. These fluid actuated cylinders are substantially the same as cylinders 60, 64, 66 and therefore the same reference numbers will be employed. On the stile 86 there is a plate 90. Again, there is a series of cylinders and plungers 60, 64 and 66 attached to the plate 90 and also to a bracket 70 associated with motor 46 and chipper 76. Likewise, associated with the chipper 74 and the motor 46 is a bracket 70.

Through FIG. 3 it is seen that the chippers 74 and 76 and the associated motors 46 are moved by the fluid actuated cylinders in a horizontal direction so that the two move closer to each other or away from each other. The chippers 74 and 76 rotate around a vertical axis so as to remove wood chips from the sides of a wood member being processed. The wood member undergoing processing upon leaving the chippers 74 and 76 is in the configuration of a cant. The lateral cross-sectional configuration may be of a square or of a rectangle.

At this time it is appropriate to summarize the combined action of the two sets of chippers 32 and 34. With reference to FIG. 6, it is seen that there is a log 94. The two chippers 36 and 38 of the set 32 will remove that cross-hatched portion of 94 identified by reference numerals 21 for the small end and 23 for the large end. At this time see FIGS. 15 and 16. With removal of the wood portion identified as 22 there is produced two substantially parallel horizontal surfaces 96. The wood member leaving the chippers 36 and 38 and entering the wood chippers 74 and 76 is identified by reference numeral 98, and has a lateral cross-sectional configuration as illustrated in FIG. 7, that portion of the wood member 98 which will be removed as wood chips is indicated by portion 24. It is seen that the chippers 74 and 76 produce a wood member 104, see FIG. 8, having two substantially parallel vertical spaced-apart sides 100. The sides 100 are substantially at right angles to the sides 96. The wood member 104 leaves the chippers 74 and 76 and enters the third set of chippers 42. The set of chippers 42 is in a frame 102 and comprises chippers 106 and 108. The frame 102 comprises a first longitudinal member 110 and a second longitudinal member 112. There is a first lateral member 114 connecting 110 and 112. There is a second lateral member 116 connecting 110 and 112. The members 110 and 112 are parallel and the members 114 and 116 are parallel. On 114 there is a plate 122. Attached to the plate

122 is a fluid actuated cylinder 60. As in FIG. 2 and associated with the chippers 36 and 38 there are a series of fluid actuated cylinders 64 and 66 associated with the chipper 106. Likewise, on 116 there is a plate 124. Connecting with this plate 124 is a series of fluid actuated cylinders 60, 64 and 66.

It is seen that the fluid actuated cylinders move the chippers 106 and 108 toward each other and away from each other. Further, it is seen that the chippers 106 and 108 are so positioned as to cut wood chips from the wood member 104 so as to have two resulting substantially parallel surfaces but which surfaces are at approximately a 45° angle with the surfaces 96 and 100 of the member 104. Another way of expressing this is it is seen that the chippers 106 and 108 chip away wood from the wood member at an angle of substantially 45° with the chippers 36 and 38 or at an angle of substantially 45° with the chippers 74 and 76.

The wood member 104 may have rounded corners between the sides 96 and 100 or sides 96 and 108 may meet at right angle. More particularly, with reference to FIGS. 15 and 16, it is seen that for the small end of the log that the adjacent sides 96 and 100 will be joined by a rounded corner. And, at the large end of the log the adjacent sides 96 and 100 will be at a right angle to each other. The set of chippers 42 remove that portion 26 of the member 104, see FIGURE 8. The wood member leaving the set of chippers 42 is identified by reference numeral 130 and has substantially parallel spaced apart sides 96, substantially parallel spaced apart sides 100, and substantially parallel spaced apart sides 132. A side 132 is at an approximate 45° angle with an adjacent side 96 and is at an approximate 45° angle with an adjacent side 100.

The wood member 130 travels to a set of chippers 44 having a chipper 134 and a chipper 136. The set of chippers 44 is in a frame 138. The frame 138 is substantially the same frame as the frame 102 and therefore like reference numerals will be used for similar components. It is to be remembered that the two frames 102 and 138 are reversed with respect to each other. On the member 114 of the frame 138 there is a plate 140. On the member 116 there is a plate 142. Attached to the plate 140 there is a series of fluid actuated cylinders 60, 64, and 66. Attached to the plate 142 there is a series of fluid actuated cylinders 60, 64, and 66. The chipper 134 is driven by a motor 46 and the chipper 136 is driven by a motor 46. The chippers 134 and 136 remove wood 28 from the wood member 130 so as to have two substantially spaced apart parallel sides 146 and identified by reference numeral 20.

It is seen that the sides 146 are substantially at right angles to the sides 132, and that the sides 100 are substantially at right angles to the sides 96. Also, a side 132 makes approximately 135° interior angle with adjacent side 96 and an adjacent side 100. Likewise, a side 146 may make an approximately 135° interior angle with an adjacent side 100 and an adjacent side 96. As previously stated, the product 20 in a lateral cross-sectional configuration has an octagonal configuration with eight (8) sides approximately the same width and each side making an interior angle of approximately 135° with an adjacent side.

There are feed rolls associated with the sets of chippers 32, 34, 42 and 44. These feed rolls in addition to assisting in the moving of the wood construction member through the apparatus 30 and the apparatus 40 also assist in positioning the wood construction member with respect to a set or sets of chippers.

These feed rolls 150 are essentially the same. They comprise a cylindrical casing 152 which is free to rotate on a shaft 154. A gusset member 156 connects with the casing 152 and also with a cylindrical casing 158. The cylindrical case 158 houses a shaft 160. On the end of the shaft 160 there is a feed roll 162. Attached to the casing 158 is a lever arm 164. As is appreciated, the

casing 158 rotates around shaft 154. There is at least one feed roll associated with each chipper. A lever arm 164 connects with the casing 158. The lever arms 164, for a set of feed rolls, may move the feed rolls toward each other or may move the feed rolls away from each other.

The shafts 160 of the feed roll 170 are in the same plane as the shafts of the chippers 36 and 38. In FIGS. 1 and 11 it is seen that there are four sets 170 of two feed rolls each whose shafts rotate in the same plane as the shafts for the chippers 36 and 38. As illustrated in FIGS. 1 and 11, the feed rolls of the sets 170 rotate in horizontal planes.

The shafts of feed rolls 172 rotate in the same plane as the shafts of the chippers 74 and 76, i.e., in vertical planes, as illustrated in FIGS. 1 and 12. In these figures is seen that there are three sets of these feed rolls 172.

The feed rolls in sets 174 rotate in the same plane and in the same direction as the chippers 106 and 108. In FIGS. 1 and 13 it is seen that there are two sets 174 of these feed rolls.

There is a set 176 of feed rolls associated with the chippers 134 and 136, and which rotate in the same plane and the same direction. In FIGS. 1 and 14 it is seen that there is one set 176 of these feed rolls.

Between the set of chippers 32 and the set of chippers 34 there is a set 170 of feed rolls. These feed rolls are in contact with substantially parallel spaced apart sides 96 and assist in positioning the wood member 98 as it moves between the set of chippers 32 and the set of chippers 34.

Between the set of chippers 34 and the set of chippers 42 there is positioned the set of feed rolls 172 and a set of feed rolls 170. The set of feed rolls 172 contacts the substantially parallel spaced apart sides 100 of the wood member 104, and a set of feed rolls 170 contacts the substantially parallel spaced apart sides 96 of the wood member 104.

It is seen that the wood member 104 is firmly positioned as it moves between the set of chippers 34 and the set of chippers 42.

Between the set of chippers 42 and the set of chippers 44 there is positioned three sets of feed rolls, 170, 172, and 174. The wood member 130 upon moving between the set of chippers 42 and the set of chippers 44 is engaged by these feed rolls. The set of feed rolls 174 engages the substantially parallel flat spaced apart sides 132. The set of feed rolls 170 engages substantially parallel spaced apart sides 96. The set of feed rolls 172 engages substantially parallel spaced apart sides 100. The set of feed rolls 174 engages substantially parallel spaced apart sides 132. In this manner wood member 130 is firmly positioned as it moves between the set of chippers 42 and the set of chippers 44.

In back of the set of chippers 44 there are four sets of feed rolls, 176, 170, 172, and 174. As product 20 leaves the set of chippers 44 and moves between these feed rolls the set of feed rolls 176 contact the substantially parallel spaced apart sides 146. The set of feed rolls 170 contacts the substantially parallel spaced apart sides 96. The set of feed rolls 172 contacts the substantially parallel spaced apart sides 100. The set of feed rolls 174 contacts the substantially parallel spaced apart sides 132.

In this manner it is seen that the product 20 as it leaves the set of chippers 44 is firmly positioned so that that portion of the wood member 20 which is still being acted upon by the set of chippers 44 is aligned so that the wood may be chipped away to give a uniform product 20 having a lateral cross-sectional configuration of a uniform octagon.

At this time the reader can appreciate that the feed rolls in conjunction with the chippers position the wood member being chipped by the chippers. With feed rolls on both sides of a set of chippers the wood member is firmly positioned in a set of chippers.

As is appreciated there must be a means for feeding a log to the first set of chippers 32. This means is identified by reference numeral 180 and is referred to as a feed table. The feed table may comprise two spaced apart carrier chain structure assemblies 182. These spaced apart carrier chain structure assemblies carry chains 184. The carrier chains 184 are mounted on sprockets 186. It is seen that each carrier chain structure support assembly 182 has a sprocket 186 at each end. There are means for rotating the sprockets 186 so that the chains will move a log 188 towards the first set of chippers 32. There are means for moving the chain 184 and the log 188 away from the first set of chippers 32 as well as towards the first set of chippers 32. Also, there are means for moving the two carrier chain structure support assemblies toward each other and away from each other to accommodate various sizes of logs. Further, there are means for moving the ends of the two carrier chain structure support assemblies 182 away from each other so that these support assemblies form a V. More particularly, those ends near the first set of chippers 32 may be moved away from each other so that there is a V or else those ends near the set 32 of chippers may be close together and those ends away from the set of chippers 32 may be moved away from each other so that there is a V.

On the carrier chain 184 there are carrier plates 190. These carrier plates 190 grip a log to be moved towards the first set of chippers 32.

Now, it can be seen that the feed table 180 grips a log so that the log is positioned both vertically and horizontally with respect to the first set of chippers 32. The first set of chippers 32 assist in positioning the log vertically. Further, the feed rolls 170 between the first set of chippers 32 and the second set of chippers 32 assist in positioning the wood member 98. Then, the second set of chippers 34 assist in positioning the wood member 98 in horizontal position. Further, the feed rolls 172 between the set of chippers 34 and the set of chippers 42 assist in positioning the wood member 104 in a horizontal position and the feed rolls 170 between the set of chippers 32 and the set of chippers 44 assist in positioning the wood member 104 in a vertical position. The set of chippers 42 assist in positioning the wood member 104 in both a vertical position and a horizontal position. The feed rolls 174 assist in positioning the wood member 130 in both a horizontal position and a vertical position while the feed rolls 170 assist in positioning the member 130 in a vertical position. The feed rolls 172 assist in positioning the member 130 in a horizontal position. Then, the set of chippers 44 assist in positioning the member 130 in both a horizontal and vertical position. The feed rolls 176 assist in positioning the member 20 in a vertical and horizontal position and the feed rolls 170 assist in positioning the member 20 in a vertical position. The feed rolls 172 assist in positioning the member 20 in a horizontal position and the feed rolls 174 assist in positioning the member 20 in both a vertical and horizontal position. In certain instances where there is a long log such as a log 80' to 100' long part of the time will be in the feed table 180 and also in the set of chippers 32, 34, 42, and 44 and the associated feed rolls. In such a situation the log is definitely firmly positioned. Other times when there is a short log such as 20 feet long, then the log may be partially in the feed table 180 and in the first set of chippers 32 and 34. With further processing of such a log, the log may be positioned between three sets of chippers, such as 32, 34, and 42 and associated feed rolls. With the feed table, sets of chippers and associated feed rolls there is assurance that there will be enough means to firmly position the wood member undergoing processing to insure a wood construction member 20 having straight sides.

At this time it is appropriate to state that the chippers 36, 38, 74, 76, 106, 108, 134 and 136 rotate with the direction of travel of the wood member undergoing processing. It has been found that with the chippers rotating with the direction of travel that a more uniform chip is

produced and a chip which can be more readily utilized in a subsequent processing operation. Also, the finished product 20 has a better surface and a smoother surface than when the chippers rotate in the direction against the travel of the wood member undergoing processing. Further, the feed rolls may be driven by means which assure constant velocity. These feed rolls may be driven by a non-overrunning feed mechanism such as a gear drive or an inertial escape mechanism. In this manner the velocity of travel of wood member undergoing processing is held relatively constant. More particularly, with the chipper knives pushing against the wood member undergoing processing there is a tendency to accelerate the speed of travel of this wood member. But by having the feed rolls move at a constant velocity these feed rolls function as a brake on the wood member undergoing processing and hold it at a relatively constant speed. With a worm gear drive there is a tendency to hold the feed rolls at a constant rotational speed and therefore the wood member undergoing processing at a constant linear speed.

20 The chippers may rotate at any reasonable speed. From experience I have found that if the chippers rotate in the range of at least 1800 r.p.m., and sometimes 3600 r.p.m., that the sides of the wood construction member 20 are smooth.

25 Reference has been made to fluid actuated cylinders such as 60, 62, and 66. It is to be realized that these fluid actuated cylinders may be a hydraulic cylinder or a pneumatic cylinder.

30 A more detailed explanation and presentation of the feed table 180 may be found in my co-pending patent application entitled, "Feed Table," Ser. No. 339,504, filing date of Jan. 22, 1964, now abandoned in favor of patent application, Ser. No. 456,019, filing date of April 23, 1965 entitled "Feed Table." Further, a more detailed and complete explanation of the apparatus 30, the apparatus 40, and the apparatus 200, with respect to the means for driving the chippers and the feed rolls may be found in my co-pending patent application entitled, "Side, Top and Bottom Chippers," Ser. No. 405,101, and filing date of Oct. 20, 1964. Further, a more detailed explanation of an appropriate chipper tooth 33 which may be used in the sets of chippers 32, 34, 42, and 44 may be found in United States Letters Patent No. 2,899,992, of E. M. Key, issuing date of Aug. 18, 1959. As is seen in the drawings there are four chipper teeth per chipper. Of course, it is to be realized that there may be a different number of chipper teeth per chipper, but from experience I have used four chipper teeth. In addition to the chipper teeth of said Key patent it may be possible to use another style of chipper tooth.

50 One of the uses of product 20 is in piling. As is generally known, piling may be made from a relatively long tree. The ends of a log are removed so as to have a pile of desirable area. A pile may have a length commensurate with the use to which it is to be placed. In some instances a pile may have a length of approximately 100' or slightly over 100'. In this situation the pile has a big area on the bigger end. In a piledriver the ways of guides are approximately 26" apart. With a large end it is necessary to cut off or chop off the large end of the pile to fit in the guides. Further, the effective area of the pile is the small end. Therefore, with a pile that tapers outwardly from the small end to the large end there is a large volume of non-usable pile. If a pile be creosoted, then there is a relatively large amount of creosote wasted on a pile which is not serving a useful structural purpose. Further, transportation of the pile is somewhat costly as non-usable piling is being transported. Also, in the driving of the pile into the ground there is a wedging effect as the small end of the pile is driven into the ground first. In extreme cases, the wedge action becomes quite large on a pile and may even prevent driving of the pile into the ground. In this regard the product 20 having a lateral cross-sectional configuration of an octagon presents a constant cross sec-

tion. There is no wedging effect of a pile in the configuration of the product 20 as opposed sides are parallel. Further, in the treating of the pile with creosote or another wood preservative there is less pile to take up the creosote or wood preservative. Further, there is less weight to transport as the excess pile has been chipped away or removed. Also, it is easier to place a pile made from the product 20 in the ways or guides of the piledriver as it is not necessary to chop away part of the pile to get in between the 26" guides. Since there is less wedging action it is easier to drive the pile in this regard and there is less weight to transport to the site of usage. Finally, the wood chips are readily salable and a profit is realized from the sale of these wood chips. In essence, there are many economic advantages the main ones being that there is realized a better pile and from a mere log and also there is realized a profit from the sale of wood chips.

From a procurement standpoint it is difficult to secure long straight piles. A curved or bent pile cannot be driven due to its susceptibility to breakage from the eccentric 20 column loading under each hammer blow. In this regard the wood construction member 20 is more readily used as it is straight.

A pile depends on skin friction for its load carrying capacity. With the wood construction member 20 used 25 as a pile there is no wedging action during the driving operation. Because of this a more accurate prediction of the driving of the member 20 as a pile can be made. The only area of the member 20 that may introduce questionable data in the bearing calculations is the end area rather 30 than the end area plus the wedge area of a tapered pile.

In addition to using the product 20 as a pile, it may be used as a pole in pole barn construction or else it may be used as an upright support in a warehouse. When used as such an upright support the smooth side may be covered with sheet metal so as to give the appearance of a metal support or as to protect the wood from undue abrasion by passing machines and trucks. With such an upright support there is less expense in producing the necessary structural features in a warehouse.

More particularly, in FIG. 17 there is a plan view of the wood construction member 20 used as a post with side wall members 200 and 202 nailed to the member 20. The two side wall members 200 and 202 are at right angles to each other. There is a corner brace 204 which is nailed to the member 20 and to the two side wall members 200 and 202. The brace 204 is at an angle of 45° to each of the side wall members 200 and 202. This illustrates the ease with which the member 20 can be used as a corner post, and that members can be easily positioned at 90° with each other and 45° with each other. As is apparent this type of construction can be used in house framing and the framing of small buildings.

In FIG. 18 there is a side elevational view of the member 20 as a post for beams 206, 208 and 210. On the sides of the member 20 there are positioned braces 210 and 212. These braces 210 and 212 are at an angle of 45° to the post member 20 and to the respective beams 206 and 208. This illustrates the ease with which the member 20 may be used as a support for beams and also braces for the beams as the braces can readily be nailed to the sides. As there are eight flat sides to the member, it is possible to readily nail a brace to one of these flat sides.

Further, the product 20 may be used as a decorative beam in house and building and lodge construction.

A further place of use for the product 20 is in fence and post construction. With logs having a small diameter of approximately 4" or 5", it is possible to realize a rail from such a log. In this regard see FIGS. 15 and 16. If the log of FIG. 15, at the small end, were 5" in diameter, at the best it would be possible to secure two two by fours (2 x 4). With the use of this invention it is possible to secure a product 20 having a lateral cross-sectional octagonal configuration of a diameter of almost the complete 75

5". In other words, the log of FIG. 15 is almost completely utilized as a structural member with respect to the small end. Further, with larger logs it is possible to convert these into guard rails having a pleasing configuration.

From the foregoing it is seen that I have provided an invention which makes it possible to utilize small logs, as well as large logs, for structural members and also to realize wood chips from these logs. In many instances, it has not been economically feasible to process small logs as there was not a sufficient amount of usable material in the log to make worthwhile the processing. With this invention it is possible to economically use these small logs as it is realized a structural member and wood chips. The value of wood chips makes possible the utilization of some of these small logs.

What I claim is:

1. An apparatus for working wood, said apparatus comprising:

- (a) a first set of two spaced apart chippers;
- (b) said two chippers being in a first plane;
- (c) a second set of two spaced apart chippers;
- (d) said two chippers of the second set being in a second plane;
- (e) said first and second planes being substantially at right angles;
- (f) a third set of two spaced apart chippers;
- (g) said two chippers of the third set being in a third plane;
- (h) said third plane being at an angle of about 45° with the first and the second planes;
- (i) a fourth set of two spaced apart chippers;
- (j) said two chippers of the fourth set being in a fourth plane; and,
- (k) said third and fourth planes being substantially at right angles.

2. An apparatus for working wood, said apparatus comprising:

- (a) a first set of two spaced apart chippers;
- (b) said two chippers being in a first plane;
- (c) a second set of two spaced apart chippers;
- (d) said two chippers of the second set being in a second plane;
- (e) said first and second planes being substantially at right angles;
- (f) a third set of two spaced apart chippers;
- (g) said two chippers of the third set being in a third plane;
- (h) said third plane being at an angle of about 45° with the first and the second planes;
- (i) a fourth set of two spaced apart chippers;
- (j) said two chippers of the fourth set being in a fourth plane;
- (k) said third and fourth planes being substantially at right angles; and
- (l) means to vary the distance between the two chippers in each set of chippers.

3. An apparatus for working wood, said apparatus comprising:

- (a) a first set of two spaced apart chippers;
- (b) said two chippers being in a first plane;
- (c) a second set of two spaced apart chippers;
- (d) said two chippers of the second set being in a second plane;
- (e) said first and second planes being substantially at right angles;
- (f) a third set of two spaced apart chippers;
- (g) said two chippers of the third set being in a third plane;
- (h) said third plane being at an angle of about 45° with the first and the second planes;
- (i) a fourth set of two spaced apart chippers;
- (j) said two chippers of the fourth set being in a fourth plane;
- (k) said third and fourth planes being substantially at right angles; and

- (l) a means for introducing a wood member to the first set of the two spaced apart chippers.
4. An apparatus for working wood, said apparatus comprising:
- (a) a first set of two spaced apart chippers; 5
  - (b) said two chippers being in a first plane;
  - (c) a second set of two spaced apart chippers;
  - (d) said two chippers of the second set being in a second plane;
  - (e) said first and second planes being substantially 10 at right angles;
  - (f) a third set of two spaced apart chippers;
  - (g) said two chippers of the third set being in a third plane;
  - (h) said third plane being at an angle of about 45° 15 with the first and the second planes;
  - (i) a fourth set of two spaced apart chippers;
  - (j) said two chippers of the fourth set being in a fourth plane;
  - (k) said third and fourth planes being substantially 20 at right angles;
  - (l) means to vary the distance between the two chippers in each set of chippers; and,
  - (m) a means for introducing a wood member to the first set of the two spaced apart chippers. 25
5. An apparatus for working wood, said apparatus comprising:
- (a) a first set of two spaced apart chippers;
  - (b) said two chippers being in a first plane;
  - (c) a first set of two spaced apart feed rolls associated 30 with said first set of two spaced apart chippers;
  - (d) said two feed rolls being in a first plane;
  - (e) a second set of two spaced apart chippers;
  - (f) said two chippers of the second set being in a second plane;
  - (g) the first plane of the first set of two spaced apart chippers being substantially at right angles to the second plane of the second set of two spaced apart chippers; 35
  - (h) a second set of two spaced apart feed rolls;
  - (i) said second set of two spaced apart feed rolls being in a second plane;
  - (j) the first plane for the first spaced apart feed rolls being substantially at right angles to the second plane for the second set of spaced apart feed rolls; 40
  - (k) a third set of two spaced apart chippers;
  - (l) said two chippers of the third set being in a third plane;
  - (m) a third set of two spaced apart feed rolls associated with said first set of two spaced apart feed rolls; 45
  - (n) said third set of two spaced apart feed rolls being in a third plane;
  - (o) the first plane for the first spaced apart feed rolls being in an angle of approximately 45° to the third plane for the third set of spaced apart feed rolls;
  - (p) the second plane for the second spaced apart feed rolls being substantially at an angle of 45° to the third plane for the third set of spaced apart feed rolls; 50
  - (q) a fourth set of two spaced apart chippers; 60
  - (r) said two chippers of the fourth set being in a fourth plane;
  - (s) the third plane of the third set of two spaced apart chippers being substantially at right angles to the fourth plane of the fourth set of two spaced apart chippers; 65

- (t) a fourth set of two spaced apart feed rolls;
  - (u) said fourth set of two spaced apart feed rolls being in a fourth plane; and
  - (v) the third plane for the third set of two spaced apart feed rolls being substantially at right angles to the fourth set of spaced apart feed rolls.
6. An apparatus for working wood, said apparatus comprising:
- (a) a first set of two spaced apart chippers;
  - (b) said two chippers being in a first plane;
  - (c) a first set of two spaced apart feed rolls associated with said first set of two spaced apart chippers;
  - (d) said two feed rolls being in a first plane;
  - (e) a second set of two spaced apart chippers;
  - (f) said two chippers of the second set being in a second plane;
  - (g) the first plane of the first set of two spaced apart chippers being substantially at right angles to the second plane of the second set of two spaced apart chippers;
  - (h) a second set of two spaced apart feed rolls;
  - (i) said second set of two spaced apart feed rolls being in a second plane;
  - (j) the first plane for the first spaced apart feed rolls being substantially at right angles to the second plane for the second set of spaced apart feed rolls;
  - (k) a third set of two spaced apart chippers;
  - (l) said two chippers of the third set being in a third plane;
  - (m) a third set of two spaced apart feed rolls associated with said first set of two spaced apart feed rolls;
  - (n) said third set of two spaced apart feed rolls being in a third plane;
  - (o) the first plane for the first spaced apart feed rolls being in an angle of approximately 45° to the third plane for the third set of spaced apart feed rolls;
  - (p) the second plane for the second spaced apart feed rolls being substantially at an angle of 45° to the third plane for the third set of spaced apart feed rolls;
  - (q) a fourth set of two spaced apart chippers;
  - (r) said two chippers of the fourth set being in a fourth plane;
  - (s) the third plane of the third set of two spaced apart chippers being substantially at right angles to the fourth plane of the fourth set of two spaced apart chippers;
  - (t) a fourth set of two spaced apart feed rolls;
  - (u) said fourth set of two spaced apart feed rolls being in a fourth plane;
  - (v) the third plane for the third set of two spaced apart feed rolls being substantially at right angles to the fourth set of spaced apart feed rolls;
  - (w) means to vary the distance between the two chippers in each set of chippers; and,
  - (x) means to vary the distance between the two feed rolls in each set of feed rolls.
